DOOR LATCH HANDLE

George M. Wills, Minneapolis, Minn., assignor to Ideal Security Hardware Corporation, St. Paul, Minn., a corporation of Minnesota

Filed Oct. 14, 1968, Ser. No. 13,963

Term of patent 14 years

Int. Cl. D8—03

U.S. Cl. D8—159

FIGURE 1 is a view in perspective as seen from the left and above of a door latch handle, showing my new design;

FIGURE 2 is an enlarged view in front elevation thereof;

FIGURE 3 is a view in side elevation thereof as seen from the right of FIGURE 2;

FIGURE 4 is a view in top plan thereof; and

FIGURE 5 is a view in bottom plan thereof.

I claim:

The ornamental design for a door latch handle, substantially as shown.
